Primary Examiner — Leanne Was-Englehart

(57) **CLAIM**

The ornamental design for a solar carport, as shown and described.

DESCRIPTION

FIG. 1.1 is a perspective view of my new design solar carport.

FIG. 1.2 is a back perspective view thereof.

FIG. 1.3 is a right-side view thereof.

FIG. 1.4 is a front-view thereof.

FIG. 1.5 is a back-view thereof.

FIG. 1.6 is an enlarged view of part of Fig. 1.1 in a different angle.

The broken lines depict portions of the solar carport that form no part of the claimed design.

1 Claim, 6 Drawing Sheets
